APPARATUS FOR SAMPLING STRIP MATERIAL

Howard H. Talbot, Pittsburgh, Pa., assignor to
United Engineering & Foundry Company,
Pittsburgh, Pa., a corporation of Pennsylvania

Application May 4, 1948, Serial No. 24,987

12 Claims. (Cl. 164—99)

1

This invention relates to apparatus for removing samples from sheet material for determining characteristics and quality of the material and, more particularly, to apparatus of this character which is capable of selecting the samples from rapidly moving continuous strip metal without interrupting the movement thereof.

Although many types of equipment have been proposed and used for this or similar purposes, it has been found that due to the bulkiness as well as slow speed of operation thereof, the forward speed of the strip from which samples are to be selected must be reduced considerably or movement of the strip interrupted entirely in order to permit positioning of the cutting dies and actuation thereof so that no ragged edges, tearing of the strip or jamming of the processing line will take place. Should this precaution not be exercised, ragged edges will occur at the section of the strip from which a sample or samples are selected and cause damage either to equipment through which the strip will be passed for further processing or to over-lapping convolutions of the strip itself if immediate coiling thereof is effected. On the other hand, should the speed of the strip be reduced or forward motion thereof interrupted entirely, not only will the output be materially affected but a considerable portion of the strip will be defective in the zone from which the sample was taken since the rolling of strip, as in a temper pass line, or the plating or pickling thereof must be accomplished at a constant speed to obtain a uniform product.

With the foregoing in mind, one of the objects of this invention is to provide apparatus for removing sample portions from rapidly moving strip material without causing damage either to the material or to the sample selected, and without involving the necessity of withdrawing the strip cutting assemblies and frame from their transverse positions relative to the strip for adjustment purposes or for re-setting the cutting elements.

Another object of this invention is to provide apparatus the cutting elements of which are adapted to be shifted transversely of rapidly moving strip material for selecting a sample therefrom at any point desired across the width thereof.

Still another object of this invention is to provide sampling apparatus having means associated therewith for retrieving a sample immediately upon the selection thereof from rapidly moving strip material with which the apparatus is associated.

2

A further object of this invention is to provide sampling apparatus having cutting elements associated therewith which may be rapidly positioned into and withdrawn from cooperative cutting relationship.

Still a further object of this invention is to provide apparatus which is rugged and positive in operation so that it is adapted to be used for sampling continuously moving strip or sheet material of various kinds and sizes.

These objects, as well as the various other novel features and advantages of this invention, will become apparent from the following detailed description and accompanying drawings of which:

Figure 1 is a plan view of the sampling apparatus embodying the features of my invention;

Figure 2 is a side elevation view of the apparatus shown in Figure 1;

Figure 3 is an end elevation view taken at III—III of Figure 1;

Figure 4 is an end elevation view taken at IV—IV of Figure 1;

Figure 5 is an enlarged section of the sampling apparatus taken at V—V of Figure 1, and

Figure 6 is a schematic diagram of the electrical control system for the sampling apparatus.

With reference to the drawings, Figures 1 through 5, the apparatus embodying the features of this invention for sampling rapidly moving strip material includes a frame consisting of a base 11, a pedestal 12 secured to one end thereof, an outwardly extending arm 13 perpendicular to and integral with pedestal 12, and a second pedestal 14 secured to the base 11 at the opposite end thereof. A plurality of flanged wheels 15 rotatably secured to the base 11 are adapted to engage with a pair of tracks 16 upon which the frame can be reciprocated to any desired position.

At the outboard end of arm 13 and upon the pedestal 14 are rotatably mounted a pair of drums 17 and 19 carrying a female die or cutting element assembly 18 and a male die or cutting element assembly 21 respectively, adapted to be placed into and withdrawn from cooperative relationship with one another, at desired intervals, for taking a sample S1 from rapidly moving strip material S passing therebetween as shown in Figure 5. Drum 17 is keyed to a shaft 22 passing through arm 13 and drum 19 keyed to shaft 23, both shafts being supported in suitable bearings provided therefor in the frame and driven through gears 24 and 25, keyed to the inboard

ends of the respective shafts and located within

pedestal 12, which, in turn, are rotated by means of a pinion 26, meshing with the lower gear 25, secured to the shaft of the variable speed electrical motor 27, having a rheostat 27a mounted on the frame thereof, attached to the base 11. For moving the frame and the elements mounted thereon along the tracks 16, a hydraulic motor 28 is provided, connected to a source of hydraulic power, not shown, supported upon a platform 28a located beneath and between the tracks 16 and having a reciprocable piston rod 29 extending therefrom secured at the outward end thereof to the frame base 11 by means of bracket 30.

Coupled to the inboard end of shaft 23 is a high speed cam type limit switch 31, to be more fully described hereinafter, mounted on a platform 32, for controlling the extension and withdrawal of the dies from their cooperative cutting positions. The platform 32 extends transversely of base 11 and is welded at the outer ends thereof to the sides of a frame reinforcing member 33 which is an integral part of the pedestal 12. A tachometer generator 34, for indicating the tangential speed of the die members 18 and 21, is driven by the variable speed motor 27 through a gear 35, keyed to the extended shaft supporting the pinion 26, which meshes with a second gear 36 secured to the shaft of the tachometer 34.

As shown in the drawings, particularly in Figure 5, the mechanism for extending and retracting the die or cutting element assembly 21 consists of a pair of solenoids 41 and 42 mounted upon a platform 39 secured to the base 11, a pair of armatures 43 and 44 respectively received therein, a bell crank 40, having arms 45 and 46, rockably mounted upon a shaft 47 supported in suitable bearings provided in reinforcing ribs 50 of pedestal 14, a pair of links 43a and 44a being secured to the exposed ends of armatures 43 and 44 and to the outer ends of arm 45, a draw bar 49 with a ball and socket joint 48 at one end thereof and within which the outer end of arm 46 is received, and two links 51 and 52, forming a toggle within drum 19, fastened at their adjacent ends to the inner end of draw bar 49 by means of a pin 53 passing therethrough. Through the outer end of link 51 a pin 54 is passed to secure the link to a cross head 55, slidable within guides 56 formed in the drum 19, and to which is secured, by a bolt 57, the die or cutting element assembly 21. The link 52 is attached, by means of pin 58, to an element 59 fastened within and to the edges of the drum 19 by bolts 61. The end of shaft 23 passes through and is keyed to the hub 62 of the drum 19. The opposite hub 63 is confined within a bearing 64 supported within the housing 65 of the pedestal 14. A bearing cap 66, secured by bolts 67 to the housing 65, is provided with a bracket 68 having an adjustable stop 69 secured thereto and against which the end of the arm 45, secured to link 43a, is adapted to strike thereby to limit the amount of upward movement thereof.

The assembly 18 consists of a hollow cylindrical die or cutting element 71 closed at one end and within which is provided a cylindrical resilient sample-ejector 72 secured to a base plate 73 through which passes a bolt 74 for retaining the assembly within the recess 75 formed on the surface of the drum 17. Two adjustable locking bolts 76 passing in an axial direction through the edges of the drum 17, engage with the cylindrical element 71 near the bottom and at diametrically opposite points thereof so that the female die assembly 18 can be positioned and

locked in place for proper registration with the die male portion 21 when a sample is to be punched from the strip.

So that the strip readily may be fed between the two rotating drums 17 and 19, the drums are flared at their edges 77, guard 78, surrounding drum 17, curved upward at its lower surfaces 79 substantially to conform to the arc defined by the flared edges 77 of drum 17, and guard 81, partially enclosing drum 19, curved downwardly together with the upper portion 82 of pedestal 14 so as substantially to conform to the arc defined by the flared edges 77 of drum 19. A guard 83, enclosing the housing 65 and the toggle operating mechanism, is secured at the top edge 84 thereof to the upper portion 82 of the pedestal 14 and at the bottom to the platform 39.

An air apron 85, positioned beneath the strip, is provided with air under pressure supplied from a source, not shown, and is attached to the pedestal 14 at the exit side of the rotating drums 17 and 19. The air apron 85 insures that a sample, which has been punched from the strip and ejected from between the dies, will positively remain above the strip and be projected into the sample retriever 86 attached to a base 87 secured to a pedestal 88 mounted on a foundation 89. A billy roller 91, the shaft of which is supported in suitable bearings 92 mounted on the pedestal 88, is provided at the exit side of the apparatus for assisting in guiding the strip downward beneath the retriever 86 to a coiling device or the like.

The control circuit for energizing and de-energizing the two solenoids 41 and 42 as shown on Figure 6 includes a plurality of relays, the first of which consists of a coil 101 and a pair of normally open contacts 101a, the second a coil 102 and two pairs of normally open contacts 102a and 102b, the third a coil 103 and two pairs of normally open contacts 103a and 103b, the fourth a coil 104 and two pairs of normally open contacts 104a and 104b, as well as two pairs of normally closed contacts 104c and 104d, the fifth a coil 105 and two pairs of normally open contacts 105a and 105b, as well as one pair of normally closed contacts 105c, and the sixth a coil 106 and two pairs of normally open contacts 106a and 106b. Also within the circuit is a push button 100 of which element 100a is normally closed and element 100b normally open. The high speed cam type limit switch 31, referred to hereinbefore, includes two cams 31a and 31b which are rotated into their closed and open positions by rotation of shaft 23 to which the limit switch 31 is connected. A two-pole fused knife switch 97 is provided, which, prior to the starting of motor 27, is closed so that power will be available for the control circuit, the "power on" condition being indicated by a lamp 98, in series with a suitable resistance 99, connected across the electrical lines L1 and L2. Two switches 107 and 108 are provided for use in case an emergency arises, being operated as a unit so that when switch 107 is opened to cut off the current from the solenoid 41, the switch 108 will be thrown to its alternate closed position whereby solenoid 42 is caused to bridge the two main electrical lines L1 and L2 and become re-energized.

The tangential speed of the rotating cutting elements can be very simply synchronized with the speed of the rapidly moving strip material, first by making a comparison of the tachometer generator reading with that of any suitable strip-speed denoting instrument which may be

associated with the moving strip preferably adjacent to the strip sampling apparatus, and, if it is found that there is a difference between the speed of the strip and the tangential speed of the rotating dies, the rheostat 27a, which is provided in the shear motor circuit, can be adjusted so that the tangential speed of the dies will coincide with the speed of the strip.

Inasmuch as variations may occur in the characteristics of the strip across the width thereof, it is desirable to remove samples from different transverse points so that they will be representative of the material from which selected. Positioning of the cutting elements at any desired transverse point is accomplished by operation of the hydraulic motor 28 which will move the cutting element supporting main frame the required transverse distance along the tracks.

When the shear motor 27 is placed in operation, the tachometer generator 34 will produce a current sufficient to energize the relay coil 101 which will cause contacts 101a to close, thereby setting up the circuit to permit the full line current to pass through and energize relay coil 102 to cause contacts 102a and 102b to close, thus to seal the second relay into the circuit. As soon as contacts 101a close, the full line current will pass through the circuit comprising normally closed contacts 104c, switch 108 and relay coil 106. Energization of coil 106 causes contacts 106a and 106b thereof to close thereby permitting the full line current to pass through and energize solenoid 42 whereby armature 44 is drawn therein positively to prevent the male die or cutting element assembly 21 from unintentionally being projected outwardly.

When a sample is to be selected from the rapidly moving strip material, the operator depresses the push button 100 causing element 100a thereof to become separated from its contacts and break the circuit in that portion of the line, and element 100b to bridge the contacts associated therewith thereby permitting full line current to pass through and energize relay coil 103 so that contacts 103a and 103b associated therewith are closed to seal the third relay into the circuit. Since the sealing into the circuit of relay coil 103 with its contacts becomes complete as soon as the push button is depressed, the operator can immediately release the push button 100 to permit the elements 100a and 100b thereof again to rise to their positions as shown in Figure 6. As will be noted in the wiring diagram, Figure 6, cam 31a of the high speed can type limit switch 31 is shown in the closed position and cam 31b in its open position. However, on rotation of the dies to a point in advance of the cutting position cam 31b will be brought into its closed position causing the full line current to energize relay coil 104 thus to close contacts 104a and 104b, sealing relay coil 104 into the circuit, and the normally closed pairs of contacts 104c and 104d to open, thereby de-energizing solenoid 42 and relay coil 102 respectively. The closing of contacts 104b permits the full line current to pass through and energize relay coil 105, switch 107 being in its closed position, so that the two pairs of normally open contacts 105a and 105b are closed and the normally closed contacts 105c opened. The closing of contacts 105a and 105b permits the full line current to pass through and energize solenoid 41 thereby rapidly drawing armature 43 into the coil and actuating the toggle mechanism associated therewith. The male die or cutting element assembly 21 is thus immediately pro-

jected outward and held in the extended position so that on further rotation of the drums 17 and 19 the two die or cutting element assemblies 18 and 21 will come into cooperative cutting relationship with the strip and remove a sample therefrom.

As soon as the cutting elements pass beyond their cutting position and are clear of the strip, the timing of limit switch 31 is such that the cam 31a thereof will move to its open position immediately to de-energize relay coil 103 thus opening the contacts 103a and 103b. The opening of contacts 103b causes the circuit of relay coil 104 to be interrupted, thereby de-energizing coil 104, which causes contacts 104a and 104b to open and contacts 104c and 104d to return to their normally closed positions. The opening of contacts 104b interrupts the flow of current to relay coil 105, thereby de-energizing the coil 105 to cause contacts 105a and 105b to open, thus de-energizing the solenoid 41. The closing of contacts 104c causes relay coil 106 again to be energized so that contacts 106a and 106b are closed and solenoid 42 energized immediately, thereby drawing plunger 44 into the coil to actuate the toggle mechanism whereby the male die portion 21 is quickly returned to its non-extended position.

In accordance with the provisions of the patent statutes, I have explained the principle and operation of my invention and have illustrated and described what I consider to represent the best embodiment thereof. However, I desire to have it understood that within the scope of the appended claims the invention may be practiced otherwise than as specifically illustrated and described.

I claim:

1. Apparatus for selecting samples from moving strip material comprising a pair of rotary carriers between which the strip passes and which are so mounted that the axes of rotation thereof are in planes at right angles to the plane of the strip, a pair of cooperating cutting elements mounted in said carriers which have such a size and shape whereby on operation a section of the strip is removed having a lesser width than that of the strip, means for selectively moving one of said cutting elements in its carrier so as to cause a cut to be made or missed as the carriers are rotated, and means for synchronizing the speed of said cutting elements with the speed of the strip.

2. Apparatus according to claim 1 having means for shifting said carriers to a pre-selected point transversely of said strip.

3. Apparatus according to claim 1 having means for retrieving a sample selected from the strip.

4. Apparatus for selecting samples from moving strip material comprising a pair of cutting elements between which the strip passes, rotatable supporting means for each of said elements, driving means for said last-mentioned means, means for shifting said supporting means to position said cutting elements at a pre-selected point transversely of said strip, means for bringing said cutting elements into and out of cooperative cutting relationship with said strip for removing a sample therefrom, control means for actuating said last-mentioned means, control means for said rotatable supporting means for synchronizing the tangential speed of said cutting elements with the speed of said strip, means for ejecting from between said elements a sample selected from said strip, and means for retrieving said sample.

5. Apparatus for selecting samples from moving strip material comprising a pair of cutting elements between which the strip passes, rotatable supporting means for each of said elements, means for shifting said supporting means to position said elements at a pre-selected point transversely of said strip, means for rotating said elements at a tangential speed coinciding with the speed of said strip, a toggle associated with one of said elements, means connected to said toggle for bringing said element into and out of cooperative cutting relationship with the other of said elements and with said strip for removing a sample therefrom, resilient means for ejecting from between said elements a sample selected from said strip, and means for retrieving said sample.

6. Apparatus for selecting samples from moving strip material comprising a pair of cutting dies consisting of a male and a female member between which the strip passes, independent rotatable supporting means for each of said members, means for shifting said supporting means as a unit for positioning said die members at a pre-selected point transversely across said strip, means associated with said supporting means for rotating said die members so that the tangential speed thereof will coincide with the speed of said strip, means for extending one of said die members into cooperative cutting relationship with said strip for removing a sample therefrom, and for returning said member to the non-cutting position thereof, resilient means associated with said female die member for ejecting therefrom a sample selected from said strip and means for retrieving said sample.

7. Apparatus for selecting samples from moving strip material comprising a frame, a pair of driven drums supported by said frame and between which said strip passes, a cutting die consisting of a female member attached to one of said drums and of a male member attached to the other of said drums, speed adjustable driving means for rotating said drums and imposing upon said die members a tangential speed equivalent to the speed of said strip material, means for extending said die male member beyond the periphery of said drum to which said male member is attached whereby on rotation of said drums said male and said female members are brought into cutting relationship with said strip, means for retracting said male member, control means for actuating said extending and said retracting means, resilient means associated with said female member for ejecting therefrom a sample received therein on completion of the cutting operation, and means for retrieving said sample.

8. Apparatus for selecting samples from moving strip material comprising a frame, a pair of driven drums supported by said frame and between which said strip passes, a cutting die consisting of a female member attached to one of said drums and of a male member attached to the other of said drums, said male member being normally so disposed with respect to said female member that upon rotation of said drums said members when in their most adjacent positions are out of cooperative cutting relationship with respect to one another, speed adjustable driving means for rotating said drums and imposing upon said die members a tangential speed equivalent to the speed of said strip material, a toggle connected to said die male member, a pair of solenoids associated with said toggle whereby upon energization of one of said solenoids said male member is projected outward, thereby to come into cooperative cutting relationship with said die female member when next adjacent thereto, and upon energization of the other of said solenoids said die male member is withdrawn to the inoperative normal position thereof, control means for energizing and de-energizing said solenoids in timed relationship with said rotating drums, resilient means associated with said die female member for ejecting therefrom a sample received therein on completion of the cutting operation, and means for retrieving said sample.

upon energization of one of said solenoids said male member is projected outward, thereby to come into cooperative cutting relationship with said die female member when next adjacent thereto, and upon energization of the other of said solenoids said die male member is withdrawn to the inoperative normal position thereof, control means for energizing and de-energizing said solenoids in timed relationship with said rotating drums, resilient means associated with said die female member for ejecting therefrom a sample received therein on completion of the cutting operation, and means for retrieving said sample.

9. Apparatus for selecting samples from moving strip material comprising a frame, a pair of driven drums supported by said frame and between which said strip passes, a cutting die consisting of a female member attached to one of said drums and of a male member attached to the other of said drums, said male member being normally so disposed with respect to said female member that upon rotation of said drums said members when in their most adjacent positions are out of cooperative cutting relationship with one another, speed adjustable driving means for rotating said drums and imposing upon said die members a tangential speed equivalent to the speed of said strip material, a pair of links connected to said male member, a bell crank, a draw bar connected at one end to said links and at the other end thereof to one arm of said bell crank, a pair of solenoids, an armature positioned within each of said solenoids, connecting links between said armatures and said bell crank, control means for energizing and de-energizing said solenoids in timed relationship with the rotation of said drums whereby said armatures are actuated and said die male member is projected into and withdrawn from the extended position thereof, a resilient element within said die female member for ejecting therefrom a sample received therein on completion of the cutting operation, and means for retrieving said sample.

10. Apparatus for selecting samples from moving strip material comprising a frame, a pair of driven drums supported by said frame and between which said strip passes, a cutting die consisting of a female member attached to one of said drums and of a male member attached to the other of said drums, said male member being normally so disposed with respect to said female member that upon rotation of said drums said members when in their most adjacent positions are out of cooperative cutting relationship with one another, means for shifting said drums to position said die members at a pre-selected point transversely of said strip, speed adjustable driving means for rotating said drums and imposing upon said die members a tangential speed equivalent to the speed of said strip material, a toggle connected to said die male member, a pair of solenoids associated with said toggle whereby upon energization of one of said solenoids said male member is projected outward, thereby to come into cooperative cutting relationship with said die female member when next adjacent thereto, and upon energization of the other of said solenoids said die male member is withdrawn to the inoperative normal position thereof, control means for energizing and de-energizing said solenoids in timed relationship with said rotating drums, resilient means associated with said die female member for ejecting therefrom a sample received therein on completion of the cutting operation, and means for retrieving said sample.

ting operation, and means for retrieving said sample.

11. Apparatus for selecting samples from moving strip material comprising a carriage, a pair of driven drums supported by said carriage and between which said strip passes, a cutting die consisting of a female member attached to one of said drums and of a male member attached to the other of said drums, said male member being normally so disposed with respect to said female member that upon rotation of said drums said members when in their most adjacent position are out of cooperative cutting relationship with one another, means for shifting said carriage to position said drums and said die members carried thereby at a pre-selected point transversely of said strip, speed adjustable driving means for rotating said drums and imposing upon said die members a tangential speed equivalent to the speed of said strip material, a pair of links connected to said male member, a bell crank, a draw bar connected at one end to said links and at the other end thereof to one arm of said bell crank, a pair of solenoids, an armature positioned within each of said solenoids, connecting links between said armatures and said bell crank, control means for energizing and de-energizing said solenoids in timed relationship with the rotation of said drums whereby said armatures are actuated to cause said die male member to be pro-

jected into and withdrawn from the extended cutting position thereof, a resilient element within said die female member for ejecting therefrom a sample received therein on completion of the cutting operation, and means for retrieving said sample.

12. Apparatus for selecting samples from moving strip material comprising a pair of carriers between which the strip passes and which are so mounted that the axes of rotation thereof are in planes at right angles to the plane of the strip, a pair of cooperating cutting elements mounted in said carriers, means for shifting said carriers to a pre-selected point transversely of said strip and means for selectively moving one of said cutting elements in its carrier so as to cause a cut to be made or missed as the carriers are rotated, said cutting elements having such a shape whereby an elliptical section of the strip will be removed.
